2,435,234

GRINDING WHEEL DRESSER

Gordon Munro, Bremerton, Wash.

Application April 20, 1945, Serial No. 589,435

9 Claims. (Cl. 125—11)

(Granted under the act of March 3, 1883, as amended April 30, 1928, 370 O. G. 757)

1

This invention relates to a grinding wheel dresser and has for an object to provide a grinding wheel dresser which will dress the grinding face of a grinding wheel and will then place the newly-dressed surface of the grinding face in the original plane of the grinding face.

A further object of this invention is to provide a means for dressing the grinding face of a grinding wheel as much as may be necessary to provide an absolutely plane grinding face and which will thereafter place the plane of the newly-dressed grinding face back in the original plane which the grinding face occupied before it was dressed.

A still further object of this invention is to provide a grinding wheel dresser particularly useful in connection with dressing a grinding wheel forming part of a twist drill grinding machine wherein the face of the grinding wheel may be dressed whenever needed and then after being dressed, the newly-dressed grinding face of the wheel may be placed in the identical plane originally occupied by the grinding face of the wheel without the necessity of using any extraneous measuring instruments whatsoever, but wherein a simple operation of the mechanism serves to dress the face of the grinding wheel any desired amount and thereafter a further simple operation moves the entire wheel transversely the exact amount that its grinding face has been dressed, thus maintaining the grinding face in the same operative position irrespective of how much or how often it may be dressed.

Still another object of this invention is to provide a grinding wheel dresser useful in the type of drill grinder shown in a companion patent application, N. C. 3691, Serial No. 589,434, filed April 20, 1945, by the same applicant.

With foregoing and other objects in view, the invention consists in the construction, combination and arrangement of parts hereinafter set forth, claimed and illustrated in the drawing in which:

Fig. 1 is a perspective, partly broken-away view of the operative parts of the dresser viewing it from beneath.

Fig. 2 is a partly sectional, partly elevational view of the grinding wheel dresser of this invention mounted in operative position.

There is shown at 10 the grinding-wheel dresser of this invention wherein a grinding wheel 11 is mounted for rotation by a motor 12 supported in a motor casing 13 mounted on a slide housing 14, which in turn is secured by means of cap screws 14' on a male slide 15. This male slide 15 is in

turn slidably mounted by means of its dove-tail key 16 in a female slide 17, which in turn is secured by cap screws 19 to a slide base 18 firmly mounted on a bed plate, table, or other supporting surface (not shown). As a result of the mechanism thus far described, it is apparent that the position of the motor 12 and grinding wheel 11 are fixed relative to the male slide 15, but are movable transversely of the plane of rotation of the motor 12 and grinding wheel 11 along the female slide 17 and its slide base 18.

When the grinding wheel 11 is used in a grinding operation, it is the face 20 that is used as a grinding surface. Hence, the face 20 wears during operation and must be dressed and then restored to its original position if it is to continue to perform its intended function. In order to do this, a dresser diamond 21 is provided on the end of a dresser arm 22, which in turn is pinned on the end of a shaft 23. The shaft 23 is journaled through the female slide 17 and has a dresser handle 24 secured to its other end.

It will be apparent that swinging movement of the dresser handle 24 will cause corresponding movement of the dresser arm 22 and dresser diamond 21 across the face 20 of grinding wheel 11. A hollow adjusting screw 25 having a knurled control wheel 26 attached thereto is maintained on the shaft 23 between a collar 27 pinned to the shaft 23 and the securing means for the dresser handle 24. The male slide 15 is provided with a depending boss 28 which is internally threaded to cooperate with the threads of the adjusting screw 25. With this construction, it will be apparent that rotation of the knurled control wheel 26 will cause axial movement of the shaft 23 relative to the male slide 15 and the grinding wheel 11 within the limits permitted by the collar 27 and a shoulder 30 provided in the bottom of the female slide 17. Another collar 31 on shaft 23 extends between the dresser arm 22 and a counterbored opening 32 in the female slide 17. A feed screw 33 journaled between a pair of collars 37 and 38 pinned thereto through a second boss 34 depending from the male slide 15 is provided with a handle wheel 35 for threading it into and out of a corresponding threaded aperture 36 in the female slide 17 to move the male slide 15 and wheel 11 relative to the female slide 17 and its supporting base 18.

The slide housing 14 surrounds the male and female slides, except for an opening on the underside to permit relative sliding movement between the slides. The slide housing thus also

functions as a shield to protect the mechanism from dust. A plate 39 having a cut-out portion in the central part is secured to the lower face of the slide housing. The plate 39 encloses the space left open by the distance by which the male slide extends beyond the female slide at either end. The female slide has cut-away portions on the lower face adjacent the slide base 18 to receive the edges of the plate 39 adjacent the opening therein. The plate 39 thus provides dust protection for the area not covered by the slide housing 14.

In operation, the dresser handle 24 may be partially rotated to move the dresser diamond 21 over face 20 of grinding wheel 11. When the grinder is assembled, the desired plane of the face 20 is exactly at the point of the dresser diamond 21 and the collar 27 on shaft 23 is simultaneously in abutting contact with the shoulder 30 of female slide 17. As the face 20 is dressed, it wears away somewhat and it is necessary to rotate the adjusting screw 25 by means of knurled wheel 26 so as to move the point 21 against the grinder wheel face 20 as long as there are any irregularities in face 20, meantime slowly swinging the dresser handle 24 back and forth until the face 20 has been dressed to a single plane.

Whatever amount of face 20 is worn off during the dressing operation will be represented by the space between the collar 27 and the shoulder 30, for in rotating the feed screw 25 the collar 27 and shaft 23 have been moved axially through the female slide 17 a distance exactly equal to the amount that the face 20 has been dressed. To bring the face 20 back to its original plane it is merely necessary to then move the grinding wheel 11 and its motor 12 together with its casing 13 back this same distance. This is done by merely rotating the feed wheel handles 35 to thread the feed screw 33 into its threaded aperture 36 in the female slide 17, thus moving the male slide 15 together with the slide housing 14 until the collar 27 again abuts shoulder 30, the dresser handle 24 having, of course, first been operated to swing the dresser diamond 21 away from face 20. This causes the male slide 15 and the parts carried thereby to move along the female slide 17 and its supporting slide base 18 a distance exactly equal to the amount that the face 20 of grinding wheel 11 has been dressed, thus bringing the newly-dressed face 20 back to the identical plane that it occupied before it was dressed.

Other modifications and changes in the number and arrangement of the parts may be made by those skilled in the art without departing from the nature of this invention, within the scope of what is hereinafter claimed.

The invention herein described and claimed may be manufactured and used by or for the Government of the United States of America for governmental purposes without the payment of any royalties thereon or therefor.

I claim:

1. A grinding wheel dresser for dressing the grinding face of a grinding wheel and then placing the newly-dressed surface of the grinding wheel in the original plane of the grinding face, said dresser comprising a base, a grinding wheel support movably mounted on said base, a dresser means mounted for dressing movement against said grinding wheel and means for moving said grinding wheel support relative to said base the exact distance that said dressing means has moved into the grinding wheel, said latter means

comprising abutting means on said dresser means and said base adapted to be separated as said dresser means moves into said grinding wheel and then be brought back into abutting position 5 to limit the movement of said grinding wheel support to the amount that the grinding wheel has been dressed.

2. Means for dressing the grinding face of a grinding wheel and for placing the newly-dressed 10 surface of the grinding face in the original plane of the grinding face comprising means for mounting the grinding wheel for movement in a direction normal to the surface of the grinding face, said mounting means including a slide on which 15 said wheel is mounted and a slide base in which said slide is relatively movable, means for mounting a dresser means for dressing movement across the grinding face to be dressed and normal to the grinding face to be dressed, said dresser means mounting means including a shaft, means for 20 moving said shaft axially as said dresser means is moved normal of the grinding face being dressed, a shoulder on said shaft, a cooperating shoulder on said slide base abutting said shaft shoulder when said dresser means and the grinding 25 face are in the original plane, said shaft shoulder being moved away from said slide base shoulder by the dressing movement of said dresser means normal to said grinding face a distance equal to the normal movement of said dresser 30 means, and feed means connecting said slide and slide base for moving said slide relative to said slide base in a direction opposite to the normal dressing movement of said dresser means, after 35 the dressing operation is completed, until said shaft shoulder and slide base shoulder are again in abutting relation, thereby placing the newly-dressed surface of the grinding face in the original plane of the grinding face.

3. A grinding wheel dresser for dressing the grinding face of a grinding wheel and then placing the newly-dressed surface of the grinding wheel in the original plane of the grinding face, said dresser comprising a base, a slide member 45 mounted on said base, said slide member supporting said grinding wheel, a depending boss on said slide, said slide base being recessed about said depending boss, a hollow adjusting screw threaded through said depending boss, a dresser shaft extending through said hollow adjusting screw and journaled through said slide base beyond said base recess, the wall of the base recess providing a shoulder, a collar pinned to said shaft within said recess providing a cooperating shoulder to abut said recess shoulder, a dresser arm on said shaft, a dresser means on said dresser arm adapted to contact the grinding face of the grinding wheel, a dresser handle on said shaft for controlling the transverse movement of said dresser arm and dresser means across the grinding face, said adjusting screw controlling the axial movement of said shaft, dresser arm and dresser means normal of the grinding face and feed screw means connecting said slide and slide 60 base and moving said slide relative to said slide base, whereby when said adjusting screw is operated to move said dressing means normally against said grinding face, said abutting shoulders are separated apart a distance exactly equal to the normal movement of said dresser means against said grinding face and then, after the dresser handle is operated to move said dresser means away from said grinding face, said feed screw means is operated to move said grinding 65 wheel slide in a direction opposite to the normal

movement of the dresser means against said grinding face until said collar shoulder abuts said recess shoulder, thereby moving the grinding wheel a distance exactly equal to the amount its grinding face has been dressed, and thus placing the newly-dressed surface of the grinding face in the original plane of the grinding face.

4. A device for dressing the grinding face of a grinding wheel, and for advancing the newly-dressed surface of the grinding face to the original plane of the grinding face, comprising means mounting the grinding wheel for movement in a direction normal to the surface of the grinding face, a base supporting said mounting means, dresser means, means supporting said dresser means on said base for dressing movement across the grinding face and for movement normal to the grinding face, feed means connecting said mounting means and said base for advancing said mounting means relative to said base, and means carried by said mounting means and cooperating with a portion of said base for limiting advancing movement of said mounting means to a distance equivalent to the thickness of material removed from the grinding face during a dressing operation.

5. In a device of the class described, a base, a grinding wheel, means supporting said grinding wheel on said base for longitudinal movement with respect to said base, means for dressing the grinding face of said grinding wheel, means for moving said grinding wheel and said supporting means longitudinally with respect to said base, and means carried by said supporting means and cooperating with said base for stopping movement of said grinding wheel and supporting means when the grinding face of the grinding wheel returns to the position occupied prior to the dressing operation.

6. In a device of the class described, a base, a grinding wheel, means supporting said grinding wheel on said base for longitudinal movement with respect to said base, means for dressing the grinding face of said grinding wheel, said dressing means including a shaft mounted for rotary and axial movement in said base, a dresser arm carried by said shaft, and means carried by said supporting means for moving said shaft axially and thereby moving said dresser arm toward the grinding face of said grinding wheel, feed means for advancing said grinding wheel and said supporting means longitudinally with respect to said base, and means carried by said shaft cooperable with said base to limit advancing movement of said grinding wheel and said supporting means.

7. A grinding wheel dresser for dressing the grinding face of a grinding wheel and then placing the newly-dressed surface of the grinding

wheel in the original plane of the grinding face, said dresser comprising a base, a grinding wheel support movably mounted on said base, a dresser means mounted for dressing movement against said grinding wheel, means for moving said grinding wheel support relative to said base, and means carried by said support and cooperating with a part of said base for limiting the distance of movement of said grinding wheel support to the distance that said dressing means has moved into the grinding wheel.

8. A grinding wheel dresser for dressing the grinding face of a grinding wheel and then placing the newly-dressed surface of the grinding wheel in the original plane of the grinding face, said dresser comprising a base; a grinding wheel support mounted for movement relative to said base, dresser means mounted for dressing movement against said grinding wheel, an abutment fixed to said base; a second abutment adjustably carried by said support in abutting relation to said first abutment when the plane of said grinding wheel is coincident with its original plane and movable out of abutting relation with said first abutment in response to relative motion between said dressing means and said grinding wheel occasioned by the dressing operation and means for producing relative movement between said grinding wheel and said base to return said abutments to abutting relation whereby the plane of said grinding wheel is returned to coincidence with its original plane.

9. In a device of the class described, a base, a grinding wheel, means supporting said grinding wheel on said base for longitudinal movement with respect to said base, means for dressing the grinding face of said grinding wheel, means for moving said grinding wheel and said supporting means longitudinally with respect to said base, and means carried by said supporting means and cooperating with a part on said base prelocated in response to relative movement between said dressing means and said grinding wheel occasioned by the dressing operation for stopping movement of said grinding wheel and supporting means when the grinding face of the grinding wheel returns to the position occupied prior to the dressing operation.
